[57] CLAIM

The ornamental design for a seat, as shown and described.

DESCRIPTION

FIG. 1 is a front perspective view of a seat showing our new design;

FIG. 2 is a side view, the opposite side being a mirror image thereof;

FIG. 3 is a front view thereof;

FIG. 4 is a rear view thereof;

FIG. 5 is a top view thereof; and,

FIG. 6 is a second embodiment of our new design, the second embodiment lacks the side arms shown in FIGS. 1 through 5.

The opposite side being a mirror image of that shown and the rear substantially like that shown in FIG. 4 without the armrest members.

1 Claim, 3 Drawing Sheets
